UNITED STATES PATENT OFFICE

JESSE WILLIAMS, OF MONROE, MICHIGAN

POLISHING DEVICE FOR ROLLS

Application filed March 27, 1931. Serial No. 525,745.

This invention relates to improvements in automatic polishing devices for rolls. In rolling mills it is customary to change the rolls between which sheet or other stock is 5 rolled at frequent intervals as the peripheries of the rolls quickly become marred. It is an object of this invention to provide a cheap and simple form of polishing device by which the surfaces of the rolls are continuously polished throughout the whole time 10 they are in operation.

Another object of the invention is to provide a roll polishing device having automatic means for continuously reciprocating 15 the polishing elements back and forth across the rolls so that uniform polishing action is exerted across their whole widths.

A further object of the invention is to provide such a roll polishing device wherein the 20 polishing elements are so mounted that they may be readily removed when worn and replaced by others.

With these and other objects and advantages in view which will become apparent as 25 the specification proceeds the invention is hereinafter more fully described with the aid of the accompanying drawings, in which:

Figure 1 illustrates a side elevation of a 30 set of rolls equipped with the invention,

Figure 2 shows a front elevation thereof, and

Figure 3 is a partial plan view.

Figure 4 is a section on the line 4—4 of 35 Figure 2, and

Figure 5 is a similar view showing one polishing element moved pivotally from its roll, and

Figure 6 is an enlarged section on the line 40 6—6 of Figure 1.

Referring to the drawings, 1 designates the usual uprights between which upper and lower rolls 2 and 3 are mounted in the conventional manner.

Secured to one extremity of the lower roll 45 3 and concentric therewith is a flange 4 having an integral extension 5 on which a sprocket wheel 6 is secured. In the uprights 1 two pair of opposed horizontal bearings 7 and 7a and 8 and 8a are arranged. Axially 50 slidable through the bearings 7 and 7a is a

transverse member 9, and axially slidable through the bearings 8 and 8a is a second transverse member 10. The members 9 and 10, which are preferably arranged one immediately over the other, are secured on one side of the machine and adjacent their extremities to the ends of a yoke 11. The latter intermediately of its length is provided with a horizontally disposed nut 12 having both right and left hand threads cut therethrough. 55

14 indicates a bearing provided in a bracket 15 secured to one of the uprights 1, and 16 denotes a second bearing provided in the adjacent upright. These bearings 14 and 16 support the extremities of a spindle 17 which is held against axial movement in any preferred manner, and intermediately of its length this spindle is provided with both right and left hand external threads to coat with either of the threads in the nut 12. 60 70 Fixed on the spindle 17 is a sprocket wheel 18 driven by the rotation of the sprocket wheel 6 through a chain 19.

Around the spindle 17 two helical springs 20 and 21 are arranged. The spring 20 extends from one side of the nut 12 to the adjacent upright 1, and the spring 21 from the other side of the nut 12 to the adjacent side of the sprocket wheel 18. In Figure 6 it will be noted that by rotation of the spindle 17 75 80 one set of cooperating threads in the nut 12 and spindle 17 have caused the yoke 11 to be moved to its limit of travel away from the adjacent upright 1, and have also compressed the spring 21. This spring then tends to move the yoke 11 towards the upright 1 and causes the other set of coacting threads in the nut 12 and on the spindle 17 to engage so that the nut, through the rotation of the spindle, 85

is moved to its other limit of travel when the spring 20 is compressed and again brings the other cooperating threads into engagement. Thus a reciprocating motion is imparted to the yoke 11 and the transverse members 9 and 10. 90

Between the uprights 1 upper and lower bell cranks 22 and 23 are so mounted on the transverse members 9 and 10 that rotary movement of the former on the latter is permitted though independent axial movement 95 100

of the former on the latter is prevented by collars 9a and 10a. One arm 22a and 23a of each bell crank supports a polishing element holder 24 and 25 respectively in which polishing elements 29 and 30 are mounted. Rotatably mounted on the second arm 22b of each bell crank 22 is a pulley 26 around which a cable 27 passes. One extremity of each cable is secured to the second arm 23b of each bell crank 23 and to the other extremity of each cable a weight 28 is secured.

From Figure 5 it will be seen that by raising the arms 22b of the bell cranks 22 the polishing elements 29 are moved away from the upper roll 2 without interfering with the operation of the polishing elements 30 which remain in contact with the lower roll 3. In operation it is frequently found that upper rolls move eccentrically to a considerable extent and it is therefore necessary to provide means whereby this eccentric movement will not interfere with the working of the polishing elements; and as it is desirable to employ the same counterweighting arrangement for holding both sets of polishing elements in contact with their rolls so that all the co-operating parts of my device occupy as little space as possible, it is necessary to provide a counterweighting arrangement wherein the eccentric movement of the upper roll above referred to will not impair the efficacy of the polishing elements in contact with either roll.

Any desired means may be employed for preventing movement of the polishing elements in their holders. One method that may be utilized is to form ends on the holders 24 and 25 as indicated at 24a and to insert blocks 32 between the adjacent ends of the elements 29 and 30.

While in the foregoing the preferred embodiment of the invention has been described and shown, it is understood that the construction is susceptible to such alterations and modifications as fall within the scope of the appended claims.

What I claim is:

1. In an arrangement of the character described, the combination of spaced uprights, upper and lower rolls extending between said uprights and rotatably mounted in the latter, transverse members supported by said uprights and movable parallel with the axes of said rolls, said members being arranged one above the other and one member being adjacent each roll, a spindle rotatably supported exteriorly of one of said uprights, means driving said spindle from the rotation of one of said rolls, a yoke reciprocated by the rotation of said spindle, one of said transverse members being secured to each extremity of said yoke so that reciprocation of the latter imparts reciprocating movement to said members, polishing element holders pivoted on

the latter, polishing elements carried by each holder, an arm projecting from each holder, guide pulleys rotatably supported by the arms extending from the upper polishing element holders, a cable one extremity of which is secured to each lower arm and extending over and partly around the guide pulley above it, and a weight secured to the opposite extremity of each cable.

2. In an arrangement of the character described, the combination of spaced uprights, upper and lower rolls extending between said uprights and rotatably mounted in the latter, transverse members supported by said uprights movable parallel with the axes of said rods, a spindle rotatably supported by one of said uprights, means for driving said spindle by the rotation of one of said rolls, said spindle intermediately of its length being provided with right and left hand threads, a nut having right and left hand threads cooperating with the threaded portion of said spindle, a yoke integral with said nut, the extremities of said yoke being secured to the extremities of said transverse members, and means for insuring that the right and left hand threads of the spindle and nut cooperate alternately so that reciprocating motion is imparted to said yoke and members, and polishing elements carried by said members.

3. In an arrangement of the character described, the combination of spaced uprights, upper and lower rolls rotatably supported thereby, opposed bearings extending transversely through said uprights, upper and lower transverse members movable axially through said bearings, means arranged exteriorly of one of said uprights for reciprocating said members when said rolls are turned, a polishing element holder pivoted about each member, polishing elements mounted in said holders so that the elements in one holder bear against one roll and the elements in the other holder against the other roll, an arm projecting from each of said polishing element holders, guide pulleys rotatably supported by the arms extending from the upper polishing element holders, a cable secured to the arm of each lower element holder and extending over and partly around the guide pulley above it, and a weight secured to the opposite extremity of each cable.

JESSE WILLIAMS.
